DES. 2385

Design to

S. H. L. Berlin of same place, J. C. Shuster & Company of Amsterdam, N. Y.,
holders Patent No. 2385, Dated Aug. 14, 1866.

Design for Coffin Trimmings.

The schedule of parts is in the above Patent, and making part of the same.

To all whom it may concern.

Be it known that S. D. D. Arnold of New Britain in
Hartford County and State of Connecticut have invented a new
Design for Coffin Trimmings; and do hereby declare that this
following is a full, clear and exact description thereof which
will enable others skilled in the art to make and use the same
reference being had to the accompanying drawing forming part
of this Specification.

The present invention consists of an ornamental
plate especially designed to be used upon coffins and other
burial cases over, and about the heads of the screws by which
the various parts of such cases are fastened together, and in the
accompanying plate my improved design is illustrated. The

Figure is a photographic view of the same,
it represents the plate which in its center is provided with an
aperture B, for the reception of the screw about the head of
which it is to be placed. This plate, upon each side of, and
above its aperture B, is ornamented with a rose C, beyond which
forming the ends of the plate, rose leaves D, extend that at each extrem-
ity of the plate are terminated by a bunch of rose buds E.

I claim as new and desire to secure by Letters Patent
The Design herein described and illustrated in the accompanying plate.
